UNITED STATES PATENT OFFICE.

WILLIAM M. THOM, OF ST. LOUIS, MISSOURI, ASSIGNOR OF ONE-HALF TO
JOHN F. MASON, OF SAME PLACE.

DRAFTING IMPLEMENT.

SPECIFICATION forming part of Letters Patent No. 268,749, dated December 5, 1882.
Application filed May 3, 1882. (No model.)

To all whom it may concern:

Be it known that I, WILLIAM M. THOM, of St. Louis, in the county of St. Louis and State of Missouri, have invented a new and useful 5 Improvement in Drafting-Instruments; and I do hereby declare that the following is a full, clear, and exact description of the same.

My invention relates to that class of drawing-instruments of the kind known as T-squares; and it consists in the peculiar combination and arrangement of a T-square, a pivoted blade having a registering-protractor, an index-hand, and a special clamping device, the whole forming a simple, easily-constructed, and accurate instrument for general drafting, and particularly for the purpose of accurately adjusting the instrument to any required angle and holding it there firmly.

Heretofore complicated and expensive drafting implements have been provided, by which these objects have been accomplished, but their expense and the care which must be observed in their use has restricted their employment to the finer kinds of work, so that 25 the need which has long existed for a simple and cheap instrument which could be made and sold at the price of an ordinary T-square has not yet been supplied.

To meet these requirements is the object of 30 the invention illustrated in the accompanying drawings, in which—

Figure 1 is a plan view of the device. Fig. 2 an end view, showing the cam fastening or locking device. Fig. 3 is a section through the 35 pivot.

In the drawings, A is an ordinary blade or straight-edge, preferably made of wood, but adapted to be made of metal, if desired. To this blade is secured by the ordinary mortise- 40 joint the fixed head B, the two parts, when in place, presenting the appearance of an ordinary draftsman's T-square.

C is a movable head, of about the same width and length as the head B, and this part C has rigidly attached to or forming an integral part of it a registering protractor, D, having a fixed scale numbered from zero in the center in both directions to ninety degrees, a segment of the semicircular portion projecting 45 beyond the fixed head when the two heads

are in line. The head C and protractor D are pivoted to the fixed head B by a central bolt, 1, passing through both the fixed and movable heads, and having a washer, 2, which bears on the lower face of the movable head. On 55 the upper end of the bolt 1 is a thumb-nut, 3, having a broad base or bearing-surface, 4, provided with an offset, 5. The bearing-surface 4 is slightly inclined, as shown in Fig. 2, to travel on the correspondingly-inclined surface 60 of a plate, 6, firmly secured to the fixed head B of the T-square, such plate also having a stop or offset, 7.

The thumb-nut, pivoted bolt, and inclined plate are preferably constructed of metal, 65 though hard wood may be used, if desired.

A stationary pointer or index-hand is secured to the fixed head B, which projects out to the protractor-scale and indicates the angle at which the movable head is turned.

In the operation of the device the head C is turned on the pivot in either direction until the hand or pointer indicates the proper angle. The thumb-nut is at this point turned to the right, wedging the inclines and drawing the 75 parts tightly together. The movable head is then used in the same manner as the fixed head in an ordinary T-square.

In mechanical drawing, where much section-shading or "cross-hatching" is required, 80 draftsmen are commonly forced to depend entirely upon the correctness of their eye for the accuracy and parallelism of the necessary lines. By my device correctness is assured so long as the proper angle has been given and 85 the movable head bears truly on the edge of the drawing-board.

This device is not intended to supply the place of the expensive and delicate instruments which are necessary for some kinds of work; 90 but as a simple, convenient, and efficient instrument for the ordinary use of draftsmen it possesses advantages which will be readily appreciated by those skilled in the art. There is also great convenience in numbering the 95 protractor-scale from the zero-point in both directions, since the blades may be readily set in opposite directions, though at the same angle, if necessary.

It will be of course understood that the en- 100

tire device may be made of metal instead of wood, and may be finished in any style commonly employed in the higher class of drafting implements.

5 I am aware of the patents of Card of 1842 and of Hoerman of 1881, and I disclaim the inventions therein set forth, the novelty of my device consisting of a novel and complete combination of essential elements not found 10 in either of said patents.

Having thus described my invention, what I claim is—

A drawing implement consisting of a blade, A, having a fixed head, B, a pivoted movable

blade, C, having a registering protractor, D, a 15 fixed hand on the head B, and a clamping device consisting of a thumb-nut having the inclined bearing-surface 4, and the plate 6, having an opposing incline, all substantially as described, and as a complete article of manufacture.

In testimony whereof I have signed my name to this specification in presence of two subscribing witnesses.

W. M. THOM.
